COAXIAL CRIMPING MACHINE

Henry William Demler, Sr., Lebanon, and Edwin Floyd, Jr., Harrisburg, Pa., assignors to AMP Incorporated, Harrisburg, Pa.

Filed July 31, 1964, Ser. No. 81,103

Term of patent 14 years

(Cl. D54—13)

FIGURE 1 is a perspective view of a coaxial crimping machine showing our new design;

FIGURE 2 is a top plan view thereof;

FIGURE 3 is a front elevation thereof; and

FIGURE 4 is a side elevation thereof.

The undisclosed rear and side are flat and unornamented.

The characteristic feature of my design resides in the specific configuration of the head portion of the machine in association with the base member as shown.

We claim:

The ornamental design for a coaxial crimping machine, as substantially shown and described.
